UNITED STATES PATENT OFFICE

WILLIAM J. DE WITT, OF AUBURN, NEW YORK, ASSIGNOR TO SHOE FORM CO. INC.,
OF AUBURN, NEW YORK, A CORPORATION OF NEW YORK

SHOE FORM

Application filed December 20, 1928. Serial No. 327,400.

This invention relates to an improvement in shoe forms, more particularly in shoe forms of the type which comprises a toe form and a thrust bar or back part stay. These shoe forms are particularly designed to keep foot wear plumped out or free from wrinkles and usually comprise a shell adapted to fit into the toe of the shoe, said shell preferably being made of celluloid or other resilient thin wall material. This invention is an improvement upon the shoe form shown in my Patent No. 1,646,016, differing therefrom in certain details of construction. The primary object of this invention is to provide an expandible shoe form which will exert lateral pressure against the material forming the toe of the shoe, such pressure being yieldably applied through a resilient thrust bar adapted to rest against the heel counter of the shoe when the form is in place, the thrust bar being so constructed that the latter can not shift out of its proper position relative thereto. A further object of the invention is to provide, in a construction of this kind, a connection between the thrust bar and the shoe form which limits swinging of the form relatively to the thrust bar, since free relative movement of the parts necessitates the use of both hands in inserting the toe form into the shoe. Another object of the invention is to provide in a form of this character, a thrust bar made of a flat strip of material and covered by a suitable fabric. Other objects of this invention appear from a consideration of the following specification taken in connection with the drawings, which form a part thereof, and in which: Fig. 1 is a bottom plan view of the forward portion of a shoe form embodying this invention; Fig. 2 is a sectional view taken along the line 2—2 of Fig. 1; Figs. 3 and 4 are views in elevation illustrating other embodiments of the invention; Fig. 5 is a view similar to Fig. 1 of another embodiment of this invention; and Fig. 6 is a sectional view taken along the line 6—6 of Fig. 5. The shoe form here illustrated comprises a shell designated by the reference numeral 10 and which comprises a pair of side walls 11 and 12 which preferably terminate at their lower edges in flanges 14 and 15. These flanges may be integrally connected at the toe as shown in Figs. 1 and 3, and are preferably in the same plane as shown in Figs. 3 and 4 so that when the form is positioned in a shoe, the flanges rest upon the inner sole thereof. The flanges 14 and 15 are connected by cross members or braces to which is secured a thrust bar. Thus in the embodiment shown in Figs. 1 and 2, the flanges 14 and 15 are connected by a single cross bar or brace 17 pivotally connected to the flange 15 by means of a rivet 18 passed through the flange and pivotally connected to the flange 14 by means of a rivet 19. The rivet 19 is free to reciprocate in a slot 20 of arcuate formation provided in the flange 14. The form of the slot 20 is such that when the rivet 19 is at the forward end of the slot the side walls 11 and 12 of the form are expanded, while when the rivet 19 is at the rear end of the slot 20 the walls are contracted. The cross bar 17 is provided intermediate its ends with a loop 22. The thrust bar 25 (Fig. 2) is provided with a loop 31 at its inner end, which engages the forward members 26 and 27 of the cross bar 17 and extends over the rearward member 28 of the loop. As shown in the drawings the thrust bar 25 is permitted a slight lateral movement in the loop 22 and may have a slight pivotal movement around the parts 26 and 27. The part 28, however, limits downward swing of the thrust bar while the rear edge of the toe form proper will limit its upward movement. The thrust bar 25 preferably comprises a flat strip of metal 30 which, at its forward end is bent back upon itself to form the loop 31. The main portion of the strip 30 forming the thrust bar 25 is preferably covered by fabric 32, the forward end of which extends into the loop 31 and may be secured there by being pinched between the tip 33 of the loop and main body of the thrust bar. The fabric covering may also be secured directly to the metal in any suitable manner, as by dipping the end of the thrust bar in 100

celluloid cement, which will hold the covering in place.

In Fig. 3 the flanges 14 and 15 of the toe form 10 are connected by a cross bar or brace 40 which may be pivotally secured to a rivet 41 fixed in the flange 15 and also pivotally secured to rivet 42, which is slidable in the slot 43 in the flange 14. The cross bar 40 is provided intermediate its ends with a pair of integral return bends 44 which extends up into the interior of the form 10. To the portion 46 of the brace 40 between the bends 44 is attached the thrust bar 47 which in the present instance may be of a resilient rod of circular cross section such as is shown in the patent above referred to. The rod 47 terminates in a loop 48 which surrounds the portion 46 of the cross bar. The bends 44 prevent any considerable lateral shifting of the toe form 10 with respect to the thrust bar 47.

Fig. 4 discloses a construction similar to that of Fig. 3 but having as the equivalent of loops 44 a pair of spaced enlargements or burrs 50 which may be formed in the body 25 of the cross bar in any well known manner. To increase the effectiveness of these enlargements, discs 51 are threaded on the bar and the loop 48^a and the forward end of the thrust bar 47^a is disposed between the discs 30 51 and thereby is held in proper relative position.

In the embodiment shown in Figs. 5 and 6, the flanges 14 and 15 of the form 10 are connected by a pair of cross bars or braces 60 35 and 61, the forward end of each brace being secured to a rivet 62 and the rearward end being attached to a rivet 63 which is free to reciprocate in a curved slot 64. As was pointed out above, when the rivets 63 are at 40 the forward ends of the slots 64, the toe form is extended, while when they are at the rear end of the slots the form is contracted. The thrust bar 65 is attached to the cross bars 60 and 61 by means of a loop 66 which surrounds 45 both members at the position where they cross. The loop 66 is substantially circular in cross-section, as shown in Fig. 6, instead of being rectangular as shown in Fig. 2. The cross braces 60 and 61 coact to prevent any 50 appreciable lateral shifting of the toe form relative to the thrust bar.

The fabric 67 which covers the flat strip 68 forming the thrust bar 65 is preferably secured in place at its forward end by the 55 engagement of the tip 69 of the loop 66 with the fabric (see Fig. 6). The fabric, however, may be secured directly to the flat strip by the use of celluloid cement as pointed out above.

It will be noted that in each of the various 60 embodiments herein described the form has only a limited movement laterally with respect to the thrust bar which is pivotally attached thereto and hence in any one of 65 these embodiments the form can easily be

inserted in the toe of the shoe by manipulation of the thrust bar alone. While certain embodiments only have been set forth I am not limited thereto since others could be made without departing from the spirit and scope of the invention as set forth in the following claims.

I claim:

1. An expandible shoe form comprising a hollow thin walled member adapted to enter the toe of a shoe and having side walls, connecting means movable to expand or contract the side walls of the member and being attached thereto, and a thrust bar pivotally joined to and adapted to move said connecting means, said connecting means including barriers which limit the lateral movement of said thrust bar thereon.

2. An expandible shoe form comprising a hollow thin walled member adapted to enter the toe of a shoe and having side walls which terminate at their lower edges in flanges, connecting means attached to said flanges and movable to expand or contract the side walls of the member, and a thrust bar pivotally joined to said connecting means intermediate the ends thereof, said connecting means having barriers which limit the lateral movement of said thrust bar thereon.

3. An expandible shoe form comprising a hollow thin walled member adapted to enter the toe of a shoe having side walls which terminate at their lower edges in flanges, connecting means attached to said flanges and movable to expand or contract the side walls of the member, and a thrust bar pivotally joined to said connecting means intermediate the ends thereof, said flange connecting means including barriers at either side of the thrust bar which limit the lateral movement of said thrust bar thereon.

4. An expandible shoe form comprising a hollow thin walled member adapted to enter the toe of a shoe and having side walls connecting means movable to expand or contract the side walls of the member, and being attached thereto, and a thrust bar pivotally joined to and adapted to move said connecting means, said connecting means including a barrier which limits the pivotal movement of the bar in one direction.

5. An expandible shoe form comprising a hollow thin walled member adapted to enter the toe of a shoe and having side walls which terminate at their lower edges in flanges, connecting means attached to said flanges and movable to expand or contract the side walls of the member and a thrust bar pivotally joined to and adapted to move said connecting means, said connecting means including barriers which limit the lateral movement of the bar in either direction and the pivotal movement thereof in at least one direction.

6. An expandible shoe form comprising a

hollow, thin walled member adapted to enter the toe of a shoe and having side walls which terminate at their lower edges in flanges, a cross brace connecting said flanges, said brace having a movement of translation relative to one flange for expanding or contracting the side walls of the member, and a thrust bar pivotally joined to the brace and adapted to move it, said brace including barriers which limit the lateral movement of said thrust bar thereon.

7. An expansible shoe form comprising a hollow, thin walled member adapted to enter the toe of a shoe and having side walls which terminate at their lower edges in flanges, a cross brace connecting said flanges, said brace having a movement of translation relative to one flange for expanding or contracting the side walls of the member, and a thrust bar pivotally joined to the brace intermediate its ends and adapted to move it, said brace including barriers at either side of the thrust bar which limit the lateral movement of said thrust bar thereon.

25 8. An expansible shoe form comprising a hollow, thin walled member adapted to enter the toe of a shoe and having side walls which terminate at their lower edges in flanges, a cross brace connecting said flanges, said brace having a movement of translation relative to one flange for expanding or contracting the side walls of the member and a thrust bar pivotally joined to the brace and adapted to move it, said brace having a loop intermediate its ends, said loop having spaced forward and rear members, the thrust bar being joined to the forward member of said loop and passing over the rear member thereof.

9. An expansible shoe form comprising a hollow, thin walled member adapted to enter the toe of a shoe and having side walls which terminate at their lower edges in flanges, a cross brace connecting said flanges, said brace having a movement of translation relative to one flange for expanding or contracting the side walls of the member, and a thrust bar pivotally joined to the brace and adapted to move it, said brace including barriers which limit the lateral movement of the thrust bar over the brace in either direction and its pivotal movement in one direction.

10. An expansible shoe form comprising a hollow, thin walled member adapted to enter the toe of a shoe and having side walls which terminate at their lower edges in flanges, a cross brace connecting said flanges, said brace having a movement of translation relative to one flange for expanding or contracting the side walls of the member, and a thrust bar pivotally joined to the brace and adapted to move it, said brace having a loop intermediate its ends, with which loop the thrust bar engages and by which loop the lateral movement of the bar over the brace is limited.

11. An expansible shoe form comprising a hollow, thin walled member adapted to enter the toe of a shoe and having side walls which terminate at their lower edges in flanges, a cross brace connecting said flanges, said brace having a movement of translation relative to one flange for expanding or contracting the side walls of the member, and a thrust bar pivotally joined to the brace and adapted to move it, said brace having a loop intermediate its ends, through which loop the thrust bar passes.

12. An expansible shoe form comprising a hollow, thin walled member adapted to enter the toe of a shoe and having side walls which terminate at their lower edges in flanges, a cross brace connecting said flanges, said brace having a movement of translation relative to one flange for expanding or contracting the side walls of the member, and a thrust bar pivotally joined to the brace and adapted to move it, said brace including a loop intermediate its ends, said loop having spaced members, the thrust bar being joined to one member of said loop and being limited by the loop in its lateral movement over the brace.

13. An expansible shoe form comprising a hollow, thin walled member adapted to enter the toe of a shoe and having side walls which terminate at their lower edges in flanges, a cross brace connecting said flanges, said brace having movement of translation relative to one flange for expanding or contracting the side walls of the member, and a thrust bar pivotally joined to the brace and adapted to move it, said brace having a loop intermediate its ends the loop having spaced forward and rear portions and the thrust bar being joined to the forward portion of said loop.

Signed by me at Auburn, New York, this 18th day of December, 1928.
